METHOD OF MAKING ELECTRIC HEATER ELEMENTS

Edwin E. Arnold, Pittsburgh, Pa., assignor to Westinghouse Electric & Manufacturing Company, East Pittsburgh, Pa., a corporation of Pennsylvania

Application June 15, 1935, Serial No. 26,847

2 Claims. (Cl. 201—64)

This invention has to do with the manufacture of heating elements for heaters of the type ordinarily known as strip heaters. Such heating elements usually consist of a resistor surrounded by a body of insulating material, which in its turn, is enclosed in an envelope or armor, usually of metal. Difficulty has been encountered heretofore in securing, in the production of such elements, sufficiently perfect thermal connection between the resistor and the refractory material surrounding it. Again imperfect thermal connection between said material and the metallic envelope has been a cause of low or uneven heat transfer, resulting in lower efficiency and shorter life than can be obtained by the methods herein set out.

I have devised a new form of resistor element which not only affords a better junction between it and the surrounding material but, by parts of its surfaces being disposed in planes at right angles, it is held firmly and prevented from being displaced during the compacting of the surrounding material under pressure. This form of resistor element also permits it to be placed on a bed of the refractory material, be covered by an additional quantity of said material, and the whole compressed together, without requiring that the resistor element be forced into the refractory material as a separate step.

A better understanding of the nature of the invention, a further knowledge of its objects and a fuller acquaintance with the details thereof may be obtained from the following description and the accompanying drawing, in which:

Figure 1 is a plan view of one form of the resistor element;

Fig. 2 is a similar view of another form;

Fig. 3 is a sectional view of a press showing one stage in the manufacture of one form of my heater element;

Fig. 4 shows a later stage of said manufacture;

Fig. 5 shows the next step therein;

Fig. 6 is a sectional view of a press, illustrating one stage in the process of making another form of heater element;

Fig. 7 is a similar sectional view illustrating the action of the press;

Fig. 8 illustrates the next stage in said process method;

Fig. 9 illustrates the stage which occurs next in the making of the form shown in Figs. 6, 7 and 8 and also the stage after that shown in Fig. 5 in the making of the first-mentioned form;

Fig. 10 illustrates the insertion of the cake shown in Fig. 5 into its envelope;

Fig. 11 illustrates the completion of the closing of the envelope of Fig. 10;

Fig. 12 illustrates the insertion of the cake shown in Fig. 8 into the envelope; and

Fig. 13 illustrates the complete closure of the envelope on the cake of Fig. 8.

A strip of conductive material of comparatively high resistance, such as is frequently used for the resistor element in heating devices, is shown at 1. This flat strip is slotted, as shown at 2 and 10 3, by slits extending alternately from opposite edges. The sinuous ribbon of resistor material thus formed comprises many members extending transversely of the strip 1.

The next step in the production of the resistor element consists in bending each of the transverse members. As shown at 5 and 6, the bends may be twists in opposite senses in adjacent strips or, as shown at 7 in Fig. 2, adjacent twists may be all in the same sense. The twists at the opposite ends of each member must be in opposite senses in order that the edges of the original strip may remain flat.

A shallow member or plate 10, shown near the bottom of the press in Fig. 3 is composed of any suitable material, preferably sheet metal, of a thickness suitable to constitute a part of the envelope or cover of the finished element. The plate preferably has its edges up-turned as illustrated at 11. The up-turned portions are of decidedly less width than the thickness of the finished heater element. The plate 10 is placed in the bottom of a trough-like arrangement upon the platen of a press and the trough is partially filled with granular, pulverant, insulating material 14. Upon this material the resistor 1 is laid and then more insulating material is placed in the trough and the plunger of the press is caused to descend thereon until the material is compressed to the thickness illustrated in Fig. 4.

During such compression some slight lateral flow of the material occurs whereby it is compacted against the side members of the trough. Because the upturned edges 11 of the plate 10 do not extend very far into the thickness of the insulating material, the lateral flow of the material during compression is greater in that portion of the insulating material immediately in contact with the resistor element than in the portion in close contact with the plate 10. To make this difference in the degree of lateral movement greater if possible, the edges of the working face 12 of the press are extended slightly toward the material being compressed, as shown at 13. This results in a rounded edge of 55

the compressed material, as shown at 15, which is nearly symmetrical to the shape produced by the up-turned portion 11 of the plate 10.

The lateral flow of the insulating material during compression takes place along the faces of the transverse portions of the resistor element. This insures a greater intimacy of contact between the insulating material and the resistor element than would occur if, instead of slight up-turned edges 11, a receptacle with side walls extending the full thickness of the compressed body had been used.

The up-turned edges 11 not only add to the stiffness of the plate 10, thus rendering the whole composite cake stiffer but they also afford a binding action between the upper edges of each up-turned portion 11, and the insulating material. The compressed material adheres thereto and thereby increases the mechanical strength of the cake as a whole and also adds to the reliability with which it is attached to the plate 10. The plate 10 is made by ordinary sheet-metal working methods and its edge, therefore, contains more or less irregularities which are sufficient to insure good bonding between the insulating material and the edge.

The trough-like receptacle in the press comprises a bottom member 16 resting directly upon the platen of the press and side members 17 adjacent to each longitudinal edge of the member 16. In the method for producing the compressed cake of Fig. 5, no insulating material comes into contact with the member 16. In the method illustrated in Figs. 6 to 8, the bottom 16 may be protected by a coating of oil, a layer of oiled paper or any other suitable means for preventing the contained material sticking to it.

This material, shown at 20, is any insulating material available in a granular form and capable of forming a coherent mass under pressure or pressure and heating. In the practice of my invention I have found zircon embedding cement convenient for this purpose. This material, like most of the insulating materials used in the manufacture of heaters, is ground to different degrees of fineness and is largely powdery in texture so if extremely dry the fine particles have a tendency to fly. I incorporate with it a sufficient amount of moisture to prevent it from flying and at the same time enough to aid in promoting load under pressure and therefore convenient handling. The moisture needed for this purpose depends upon such factors as the presence of small additions of clay bond in the mixtures and upon the fineness of the granular material. I have found, under some circumstances, as little as 5% of moisture sufficient and, under some circumstances, considerably more moisture can be used to advantage but not enough moisture must be used to make the mixture liquid or unworkable.

The trough is partly filled with such insulating material 20 and the resistor element 21 is laid thereon. Then more of the same resistor material is put into the trough until it is filled to the desired height. It is not necessary to thrust the resistor element into the embedding material but is sufficient for the purposes of this invention to place it upon the surface of the portion of the embedding cement already in the trough.

When the resistor is in place and covered by the insulating material the plunger 12 of the press is caused to descend thereon. Sufficient pressure is exerted by the plunger to compress 75 the material into a cake 22 of approximately one-

third of the thickness of the material when first introduced into the press, as is shown in Fig. 7.

In this compressed state the cake 22, not having a plate like 10 of Fig. 5, has not sufficient mechanical strength to stand ordinary handling by unskilled workmen. The most convenient way of handling the cake in this condition is to support it upon a base 23. This base is preferably of iron or steel and is so thick that it will support a long cake without sagging during handling. It is much stiffer, even when hot, than the finished heater element. Even the cake 14, made by the first-described process, although mechanically stronger than the cake 22, is more conveniently handled if supported, as shown at 23 in Fig. 5. The most convenient way to transfer the cake 22 from the bottom 16 of the trough to the support 23 is to slide the cake end-wise out of the trough onto a base which has been placed end to end with the trough. If desired, the side members 17 may be made removable and the bottom 16 may be tipped to cause the cake 22 to slide onto the base placed beside it. Or the member 16 and the cake 22 may have the base 23 placed on top of them and the whole combination rotated through 180° to bring the cake 22 onto the base 23.

The cake 22 on its base 23 is then put into an oven for baking. The cake 14, with or without a base 23, is put at this stage into a similar oven and the process from this point on is similar for either form of cake. The oven is shown in Fig. 9 and is preferably equipped with ribs 25 upon which the base 23 rests. This affords a clearance between the base 23 and the bottom of the oven so that a fork or other tool for handling the cake and base may be readily inserted under the base 23.

The cake is baked in the oven until it acquires sufficient mechanical strength to be handled without the support of the base. I do not regard my invention as limited to any particular degree of baking. The degree of baking should be sufficient to remove the moisture. I have found that this baking may be at desiccating temperature to as high as a red heat depending upon the structure and composition of the embedding material, followed by a sufficiently slow and even cooling operation to avoid cracking.

When the baking is finished, the cake and the base 23 are removed from the oven and the cake is inserted in its envelope. This may be done by depositing the cake 22 upon the flat member 30 of the envelope, Fig. 12, but the cake is now strong enough so that it may be lowered or even dropped into a trough-shaped member of the envelope if there is any reason for preferring this procedure.

In the preferable method of inserting the cake 14 into the envelope the portion 31 of the envelope Fig. 10, which has a depth exceeding the thickness of the cake, is provided with oblique margins at the free edges of the side portions, as shown at 32. The cake 14 is inserted into the member 31 by sliding it in from one end. The edges 11 of the shallow member 10 glide upon the oblique margin portions 32 or against the side portions of the deep member 31 during such sliding motion. When the cake is in place within the envelope, the portions 32 are pressed against the external face of the member 10, thereby completing the closure of the envelope, Fig. 11. This method of assembling the device avoids the necessity of a curling or crimping action for closing the envelope, a simple, direct thrust be- 75

ing sufficient. It is not necessary that this thrust be of sufficient force to compress the material of the cake 14, this having been sufficiently compressed in the operation illustrated in Fig. 4.

With the form of cake illustrated in Fig. 8, it is necessary to provide a plate 30 because no part of the envelope is associated with the cake 22 during the preceding parts of the process. If the cake 22 is not deposited on the strip 30 as already described, the cake may be slid endwise into the member 31 and the plate 30 may be put in place by a separate sliding action or it may be deposited on the cake and the two slid together. When the cake 22 is in position in the envelope, the edges 32 are closed upon the plate 30 in the same way as described in connection with Figs. 10 and 11. This action is illustrated in Figs. 12 and 13.

Although after the cake has been baked it has sufficient mechanical strength to be handled in other ways, the endwise sliding of the cake into this envelope is preferred, because it subjects the cake to fewer mechanical shocks and strains and results in a smaller loss by breakage in the manufacture of the heater elements.

Openings are provided at the end of the casing for the projection of terminals which are formed integral with the ends of the resistor strip 1. Since these terminals form no part of the present invention, they are not herein illustrated or more specifically described.

When the device has thus been manufactured it is submitted to a test. During this test the resistor 1 is heated by electrical current therethrough and heats the surrounding material. Any moisture which is left in the cake after the baking in the oven is evaporated during this test and escapes, principally through the joints between the margins 32 and the shallow member 10 or 30. Some moisture probably also escapes at the ends of the element where the openings for the terminals are provided.

I have not found it necessary to compress the casing, although no harm results if the action of folding the margins 32 incidentally exerts some pressure on the cake. Ordinarily mechanical skill usually affords a connection between the element 1 and the radiating surface of the casing having sufficient thermal conductivity.

When better thermal connection between the metallic envelope and the cake is particularly desired, I have found it practical to treat the surface of the cake with a slurry. Any inorganic electric insulating material capable of forming a good thermal joint between the cake and the envelope will serve as a slurry. I prefer an aqueous suspension of material similar to that used to form the cake. Again it is practical to paint the cake with such a slurry, place it in an open casing, such as a trough, without the accompanying cover, and bake it in this condition before placing the cover on the trough.

Again the procedure may be to paint or spray the inside of the trough with the slurry and then place or slip in the formed cake. This has some advantage in securing more even distribution on the surface by reason of the non-absorbent nature of the trough surface.

I do not find it necessary to use such a slurry, but on the other hand, I have found that it can be used and the casing put in place and then dried by heat supplied either specially for the purpose or during the testing of the element.

The good bond which I have thus secured between the members 30, 31 and the insulating material is productive of a higher rate of heat transfer and thereby increased efficiency of operation.

The transverse members of the sinuous resistor element are short, extending only the width of the strip. During this expansion and contraction in the use of the heater, the relative movement between them and the resistor material is not sufficient to break the bond. Moreover, expansion and contraction of the device as a whole is most evident in the direction of the length of the strip and the resistor element is capable of very considerable stretching or contraction in the direction of its length without introducing strain. Any force tending to produce relative motion between the resistor and surrounding material in the direction of the length of the strip is resisted by pressure of the faces of each transverse member flat-wise against the insulation. The faces of the transverse members are normal to the line of action such forces throughout almost the entire length of each of said members. The bonding action of the transverse members is effective not only in preventing thermal expansion from causing separation but also in preventing such separation of resistor and insulation during bending of the heater element.

A heater element made in this way can be bent to fit cylinders or curved surfaces without detrimental effect on the insulating qualities of this structure.

Many variations in the process herein described will occur to those skilled in the art and I do not desire to be restricted to the exact materials mentioned herein or the exact details of the several steps in the process.

I claim as my invention:

1. The process of making an element for an electric heater comprising a resistor element, compressible electric-insulating material therearound and an enclosing metallic envelope having a shallow member and a deep member of greater depth than the thickness of the finished element, which includes the steps of depositing a bed of compressible electric-insulating material upon said shallow member, placing a resistor element on the surface of said bed, depositing additional insulating material on said element and bed, compressing the deposited material into good bonding contact with the resistor element and with the shallow member, baking the compressed bonded body, inserting the baked body into said deep member and clamping said members together.

2. The process of making a heater element comprising a resistive conductor surrounded by insulating material and enclosed in a metallic envelope, which includes the steps of making an elongated shallow envelope member, making an elongated envelope member of a depth greater than the thickness of the insulating material in the finished article with inwardly inclined margins at the edges of its sides, making a cake comprising the resistive conductor surrounded by insulating material and bonded to the shallow member, then inserting said cake with the shallow member endwise into said deep member and flattening the margin against the shallow member.

EDWIN E. ARNOLD.
